UNITED STATES PATENT OFFICE.

PAUL GROEBLI, OF NEW YORK, N. Y.

DESIGN FOR LACE.

Application filed September 30, 1925. Serial No. 14,966. Term of patent $3\frac{1}{2}$ years.

To all whom it may concern:

Be it known that I, PAUL GROEBLI, a citizen of Switzerland, residing at 603 W. 111th Street, borough of Manhattan, city, county, and State of New York, have invented a new, original, and ornamental Design for Lace, of which the following is a specification, reference being had to the accompanying drawing, forming part thereof.

The figure is a plan view of the lace, showing my new design.

I claim:

The ornamental design for lace substantially as shown.

PAUL GROEBLI.
